UNITED STATES PATENT OFFICE.

JOSEPH B. LONG, OF CHICAGO, ILLINOIS.

DESIGN FOR A CADDY.

SPECIFICATION forming part of Design No. 33,526, dated November 6, 1900.

Application filed August 20, 1900. Serial No. 27,510. Term of patent 3½ years.

To all whom it may concern:

Be it known that I, JOSEPH B. LONG, a citizen of the United States, residing at Chicago, in the county of Cook and State of Illinois, 5 have invented and produced a new and original Design for Caddies, of which the following is a specification, reference being had to the accompanying drawings, which are made a part of said specification, and in which—
10 Figure 1 is a perspective view of a caddy embodying the new design. Fig. 2 is an end elevation thereof with the legs broken.

A caddy of the new design has a body the back and end walls of which are flat and 15 vertical, while its front wall comprises a central panel C, the outer surface of which is curved in vertical planes, and two rectangular panels C' C', the outer surfaces of which are flat, flanking the panel C at its ends, the 20 three panels C C' being surmounted by a narrow raised strip or rib D, extending from end to end of the body and having along its horizontal margins inturned flanges d. The top of the caddy comprises a narrow portion E, 25 disposed horizontally, a plurality of lids F, which are of curved cross-section and which present the appearance of sunken curved panels, their end margins being covered and

concealed by curved ribs or strips, and a narrow raised strip or rib e, disposed between E 30 and F. The upper margins of the ends G are curved to correspond with the lids F. The body is supported by legs H at its four corners.

The leading essential features of the new 35 design are the body having the front divided into a panel C, the outer surface of which is curved in vertical planes, the panels C', flanking the panel C at its end and having flat outer surfaces, and the curved lids F, 40 presenting the appearance of sunken panels.

A minor feature of the design is the narrow raised strip or rib D, extending from end 45 to end of the body and disposed above the panels C and C'.

What I claim as new, and desire to secure by Letters Patent, is—

The design for a caddy substantially as herein shown and described.

Signed at Chicago, Illinois, this 30th day of 50 July, 1900.

JOSEPH B. LONG.
